UNITED STATES PATENT OFFICE.

CHARLES VALENTA, OF CHICAGO, ILLINOIS.

ENVELOP.

1,148,874.

Specification of Letters Patent.

Patented Aug. 3, 1915.

Application filed October 15, 1914. Serial No. 866,770.

To all whom it may concern:

Be it known that I, CHARLES VALENTA, a citizen of the United States, and a resident of the city of Chicago, county of Cook, and 5 State of Illinois, have invented certain new and useful Improvements in Envelops, of which the following is a specification.

My invention relates to improvements in mailing envelopes and has for its object the 10 production of an envelop which may be readily and easily opened or severed.

A further object is the production of an envelop which will be of simple construction and efficient in use.

15 Other objects will appear hereinafter.

The invention consists in the combinations and arrangements of parts hereinafter described and claimed.

The invention will be best understood by 20 reference to the accompanying drawing forming a part of this specification, and in which

Figure 1 is a perspective view of an envelop, in partly formed condition, embodying 25 my invention, Fig. 2 is an elevation of the envelop in sealed condition, and Fig. 3 is a view similar to Fig. 2 showing the envelop severed.

The preferred form of construction as 30 illustrated in the drawing comprises an envelop formed of paper or like material consisting of a rectangular central portion 1 which, when the envelop is completed, forms the front side thereof, and flaps 2, 3, 4 and 5 35 which are adapted to be overlapped and secured together as is readily understood to form the back of the envelop. The flap 3 is left unfastened until after the mailing matter has been inserted into the envelop, 40 whereupon said flap may be fastened in the usual manner to close the envelop.

Arranged along one edge of the envelop under the flap 2 is a cord 6. One end of said cord is secured, as by tying, to an ear 45 7 formed upon the flap 5 as clearly shown in Fig. 1. Said ear 7 is provided at its outer edge with a notch 8 in order to prevent disengagement of the cord 6 therefrom. The cord 6 is coextensive with the adjacent edge 50 of the envelop and the opposite end thereof is formed into a loop 9 the bight of which projects exteriorly as clearly shown in Figs. 1 and 2. The extremity 10 of the looped end of said cord is releasably fastened as by 55 gluing or pasting under an ear 11 which is

formed upon the flap 4. Through the provision of the ear 11 the fastening of the extremity 10 in proper position is greatly facilitated and is securely held to prevent accidental disengagement or withdrawal 60 thereof.

With the arrangement disclosed it will be seen when it is desired to open or sever the envelop it is only necessary to engage the exteriorly projecting bight portion of loop 65 9 between the thumb and finger and pull the same outwardly so as to cause said cord to sever the adjacent edge of the envelop as clearly shown in Fig. 3. With this arrangement it will be seen that an envelop may be 70 readily and easily opened and without fear of injury to the contents of the envelop such as is frequently the case where the envelop is opened by severing one edge thereof with a sharp tool or scissors. A loop 9 is formed 75 at the end of cord 6 instead of just permitting the end of said cord to project exteriorly, in order to afford a better grip for engagement by the fingers, it being clear that without the provision of said loop the 80 fingers would be liable to slip from engagement with the cord in the severing operation.

While I have illustrated and described the preferred form of construction for carrying 85 my invention into effect, this is capable of variation and modification without departing from the spirit of the invention. I, therefore, do not wish to be limited to the precise details of construction set forth, but 90 desire to avail myself of such variations and modifications as come within the scope of the appended claims.

Having described my invention what I claim as new and desire to secure by Letters 95 Patent is:

1. The combination of an envelop; a severing cord arranged in said envelop along one edge thereof, said cord being coextensive with said edge; and an ear on said envelop 100 at one end of said edge embraced by one end of said cord for anchoring the same to the envelop, said ear being notched at its outer edge for the reception of said cord, the opposite end of said cord projecting exteriorly, 105 substantially as described.

2. The combination of an envelop; a severing cord arranged in said envelop along one edge thereof, said cord being coextensive with said edge; and an ear on said envelop 110

at one end of said edge embraced by one end of said cord for anchoring the same to the envelop, said ear being reduced in width at the point of engagement at the end of said 5 cord, the opposite end of said cord projecting exteriorly adjacent the opposite end of said edge, substantially as described.

In testimony whereof I have signed my name to this specification in the presence of two subscribing witnesses.

CHARLES VALENTA.
